MOP HOLDER AND FOUNTAIN SPRAY
DEVICE

Louis Myshock, Detroit, Mich.

Application April 4, 1951, Serial No. 219,292

4 Claims. (Cl. 299—112)

1

The holder has been designed for use with a mop including an oblong sleeve, the holder and the mop being normally curved into a loop. The holder of my invention is of a novel and useful construction, including novel interlocking means between its ends. Additionally, the holder is of a type which is adapted to convey water or other liquid to the mop which is mounted on said holder. Another feature of my improvement is the fact that the holder is devoid of all metal parts, thus eliminating the danger of cutting or scratching objects which in the operative use of the mop may come in contact therewith.

This and other features will now be described with reference to the accompanying drawing in which:

Fig. 1 is a plan elevational view of my holder, the holder being equipped with a handle and supporting a conventional sleeve-equipped mop;

Fig. 2 is a plan elevational view of the holder with the handle therein, the holder and the handle being shown partly in section;

Fig. 3 is an enlarged sectional view of the handle-receiving portion of the mop holder and of the adjoining part of the body thereof;

Fig. 4 is a sectional view of the handle-receiving portion of the holder, the view having been taken on line 4—4 of Fig. 3;

Fig. 5 is a perspective view of an element of my holder.

Similar numerals refer to similar parts throughout the several views.

The mop holder of my construction is preferably made of rubber or some other flexible material and includes a tubular member 10 closed upon itself to form a circular loop. The loop is provided with an integrally-connected shank 11 disposed in radial relation to said circular loop. The shank is hollow to form a socket 12, the interior of the socket opening into the interior 13 of the tubular member 10. The latter extends laterally from the shank, as best shown in Fig. 3, and terminates with a solid end 14, the end having flat sides and a corrugated, that is, an indented, surface 15. Said end is adapted to enter the interior of said shank 11. For that purpose the shank is provided with a slot 16 opening from the outside into said shank and having flat sides 17 and a bottom 18 which is indented or corrugated in a manner analogous to that shown at 15 in the above-said solid end 14. At their inner ends the sides of the slot flare out, as shown at 19.

It will be noted that the interior of socket 12 opens into the interior 13 of member 10. The

latter member is provided with a plurality of small holes 20 all along its length for discharge of water or any other liquid from the interior of said member. The socket 12 is threaded internally, as shown at 21, for reception of a handle 22, the handle being correspondingly threaded externally at one end, as shown at 23. The handle is preferably hollow, as shown at 24, although a solid handle may be used with my holder when no liquid is to be conveyed into the holder. Figs. 1 and 2 show the position of the handle within the socket 12 of my holder.

The mop which is supported by the holder is shown in Fig. 1 and indicated generally by numeral 25. The sleeve part of the mop is indicated by numeral 26 and the loose cords of the mop are marked 27.

The use of the holder is quite obvious. Assuming that the solid end 14 of the tubular member 10 is out of slot 16 in the shank 11, the sleeve 26 of the mop 25 may be thrust upon the tubular member 10 at that end until it covers the length of said member 10 with the exception of its portion adjoining the shank itself. This is shown in Fig. 1. Thereupon, said solid end 14 may be inserted into slot 16 so that individual teeth or corrugations 15 will fit the corresponding corrugations 18 within said slot. The sides of end 14 will abut in a liquid-tight manner the sides 17 of the slot. It will be seen that said end 14 reaches inwardly into the shank approximately up to the center thereof, leaving a free passage marked by an arrow for admission of water from socket 12 into the interior of member 10. The handle 24, when screwed into said socket 12, will bear against the top of the solid end 14 of member 10, holding said end 14 in an interlocking engagement with teeth 18 within the shank so that said end may not be withdrawn from slot 16. Water or any other liquid admitted into the handle from its outer end will pass from said handle into the tubular member 10 and will be disposed through holes 20 towards the sleeve 26 and the loose cords 27 of the mop.

If the mop is to be removed from the holder the handle may be partly unscrewed, permitting the withdrawal of solid end 14 from the slot 16, whereupon the mop may be removed from said member 10.

It will be understood that some changes may be made in the construction of my holder without departing from the inventive idea disclosed herein.

What I, therefore, wish to claim is as follows:

1. In combination, a mop holder having a

shank provided with an internally threaded socket and being provided on one side with a lateral slot opening into said socket from outside, the bottom of the slot being indented and facing the interior of said socket, an integrally formed flexible body radially extending from the shank at its opposite side, said body describing a loop and terminating with an end adapted to enter said slot, said end having an indented surface for engagement with the indented bottom of the slot, and a handle having a threaded end for insertion into the socket, said threaded end being adapted to bear against the end of the flexible body within the slot to cause the indentations of said end to interlock with the indentations within the slot.

2. In combination, a mop holder having a shank provided with an internally threaded socket and being provided on one side with a lateral slot opening into said socket from outside, the bottom of the slot being indented and facing the interior of said socket, an integrally formed flexible body radially extending from the shank at its opposite side, said body describing a loop, the body being tubular and provided all along its length with a plurality of holes in its wall and terminating with a solid end adapted to enter said slot, said end having an indented surface for engagement with the indented bottom of the slot, and a tubular handle threaded at one end for entry into said socket, said end of the handle being adapted to bear against the end of the flexible tubular body within the slot to cause the indentations of said end of the flexible body to interlock with the indentations within the slot, the interior of the socket opening into the interior of said flexible body.

3. A mop holder of the kind described, said holder comprising a shank having a threaded socket therein, a flexible tubular body integrally connected to the shank and radially extending

from one side thereof to form a loop, the body terminating with a solid corrugated end, the opposite side of the shank being provided with a corrugated slot opening thereto from outside, 5 the solid end of the tubular body of the holder being adapted to be inserted into said slot for an interlocking engagement with said slot, the interior of the shank opening into said tubular body, the wall of the latter being provided with a plurality of holes for release of liquids conveyed into the tubular body of the holder.

10 4. In combination, a holder of the kind described, said holder comprising a shank containing a threaded socket therein and being provided with a laterally-disposed slot opening into the socket from outside, the bottom of the slot being provided with corrugations facing the interior of the socket, a flexible tubular body extending radially from the shank describing a loop and terminating with a solid end, the end having corrugations thereon, a tubular handle having a threaded end to fit into said socket, said end of the handle being adapted to bear against the solid end of the body to interlock the corrugations thereof with the corrugations within the slot, the interior of the socket being open into the interior of the tubular body of the handle while the wall of the holder is provided with a plurality of holes for discharge of liquids from 15 20 25 30 35 40 within said holder.

LOUIS MYSHOCK.
